UNITED STATES PATENT OFFICE.

WILLIAM H. NUTTER, OF SHELTON, NEBRASKA.

HAT-PIN GUARD.

1,089,949.

Specification of Letters Patent. Patented Mar. 10, 1914.

Application filed November 26, 1912. Serial No. 733,694.

To all whom it may concern:

Be it known that I, WILLIAM H. NUTTER, a citizen of the United States, residing at Shelton, in the county of Buffalo and State 5 of Nebraska, have invented new and useful Improvements in Hat-Pin Guards, of which the following is a specification.

This invention relates to a hat pin guard designed particularly for use on points of 10 hat pins and serving in use to effectively guard the point of the pin.

The main object of the present invention is the provision of a hat pin guard of similar structure and including a similar movable part, the clamping action of the pin point being automatically maintained and released by a simple manipulation.

The invention in its preferred form of details will be described in the following specification, reference being had to the accompanying drawing, in which:—

Figure 1 is a sectional view showing my improved pin guard in place. Fig. 2 is a front elevation of the guard.

Referring particularly to the accompanying drawings, my improved pin guard comprises a body member 1 which is preferably of semi-circular shape. The body may be hollow and may be otherwise shaped, 30 though the shape described is preferred in order that the flat portion thereof may provide a means for the connection of any suitable ornament thereto. The rounded surface of the body is formed with a flaring 35 pin opening 2 in which the point of the hat pin 3 is inserted.

Within the body is arranged the locking member which comprises a suitable length 40 of spring material secured at one terminal as 4 to the base of the body projected therefrom in a plane curved toward the opposite surface of the body, as at 5, and then formed in a return loop as 6, projected in a straight line toward the opening 2, as at 7, and terminally formed with an angularly bent portion 7' to be engaged by a finger piece 8 which projects through a slot 9 in the wall 45 of the body. The portions 5 and 7 of the locking member are formed with pin-receiving openings 10, and these openings are so disposed that when the spring is fully compressed, that is, by the complete depression of the finger piece 8 so that when the section

7 is at its limit of inward movement the openings 10 in said curved sections are in 55 alinement with the pin-receiving openings 2 in the body.

After the introduction of the pin point, which is accomplished with the spring fully compressed it will be obvious that upon release of the pressure the spring sections tend to return to normal position separating the sections 5 and 7. This movement will operate toward moving the opening 10 in the section 7 out of alinement with the opening 10 in the section 5. This action will exert a frictional binding upon the pin point of sufficient force to hold the guard in place and prevent its accidental separation from the pin. When it is desired to separate the 70 pin from the guard the spring is again compressed as will be obvious relieving the frictional engagement and releasing the pin.

Aside from the details noted the guard may be of any shape and ornamented as desired, the use of any appropriate material and a construction of the guards in any desired size being contemplated.

What is claimed is:

A hat pin guard including a body comprising a flat plate and a rounded cover rising therefrom, said cover being formed with a pin receiving opening, and a locking member arranged wholly within the body and comprising a single length of spring 80 material bent to provide a bowed portion and a projection extending angularly from one terminal of said bowed portion, the ends of said bowed portion bearing upon said plate, said angular projection toward and 85 past the opening in the cover, the angular projection and bowed portion of the locking member being formed with openings adapted to aline with each other and with the opening in the cover in a certain position of 90 the portions of said member other than normal, and means for operating one of the portions of said member to move the portions into such relative position.

In testimony whereof I affix my signature 95 in presence of two witnesses.

WILLIAM H. NUTTER.
